UNITED STATES PATENT OFFICE.

TULLY GRAYBILL, OF CUMBERLAND, MARYLAND, ASSIGNOR TO KELLY-SPRINGFIELD
TIRE COMPANY, OF CUMBERLAND, MARYLAND, A CORPORATION OF NEW JERSEY.

DESIGN FOR A VEHICLE TIRE.

Application filed December 29, 1923. Serial No. 8,184. Term of patent 14 years.

To all whom it may concern:

Be it known that I, TULLY GRAYBILL, a citizen of the United States, residing at Cumberland, in the county of Allegany and State of Maryland, have invented a new, original and ornamental Design for a Vehicle Tire, of which the following is a specification, reference being had to the accompanying drawing, forming a part hereof.

The figure is a partial section of the tire, in perspective, showing my new design.

I claim:

The ornamental design for a vehicle tire as shown.

TULLY GRAYBILL.
